(54) **BEDSTEAD BOLTS**

(76) Inventor: **Ira M. Laughlin**

Ira M. Langlin of Sunderland, Vermont.

Letters Patent.

The schedule referred to in these Letters Patent and making part of the same containing a description in the words of Ira M. Langlin of his improvement in the manner of Bolting Bedstead Joints

To all to whom these presents shall come,

Be it known that I, Ira M. Langlin of Sunderland in the County of Bennington and State of Vermont, have invented a new and useful improvement in the manner of bolting bedstead joints and that the following is a full and exact description thereof. Pass an iron screw bolt diagonally through such post directly between the mortises which receive the tenons on the rails and also through the wood or iron bar formed into the nail, directly across the corner not so near as to touch the post, the bar may be curved so as to form a gentle hook on the ends that are received into the nail; By receiving the nail against the bar, the posts are held firmly against the shoulder of the rails.

What I claim as my own invention and not previously known in the above described bedstead is the peculiarity wherein in which one bolt is made to hold two posts.

Witness,

James Maron
Louis Ward.
